AUTOMATIC BURNER CONTROL SYSTEM

Robert S. Craig, Robbinsdale, Minn., assignor to
Minneapolis-Honeywell Regulator Company,
Minneapolis, Minn., a corporation of Delaware

Application June 18, 1941, Serial No. 398,611

3 Claims. (Cl. 158—28)

This invention relates generally to automatic systems for controlling fuel burners and is more particularly concerned with simple and inexpensive systems in which a timed trial ignition period as well as protection against flame failure are necessary.

One of the main objects of the present invention is to provide a system which employs the usual thermally timed safety switch, a two wire combustion switch, and an electrical means for controlling the fuel feed, wherein the parts are so arranged that the scavenger period is timed by the combustion responsive switch, and the system checks itself each cycle for a burned out heater for the thermal timer. In addition, the system is so designed that it will open the safety switch a predetermined time after a flame failure and will therefore not recycle.

These and other objects will readily become apparent as the following specification is read in the light of the accompanying drawing in which the single figure illustrates schematically an oil burner control system embodying my invention. Although this system will be described as an oil burner control system, it will readily be appreciated that this invention may be adapted for use in systems controlling various other types of fuel.

Referring now to the drawing, the reference numeral 10 indicates generally the usual type of room thermostat comprising a bimetallic element 11 which is fixed at one end and which carries at its free end a pair of resilient contact blades 12 and 13 which cooperate respectively with stationary contacts 14 and 15. The blades and contacts are so arranged that on a decrease in temperature the contact blade 12 will first engage contact 14 and at a slightly lower temperature the contact blade 13 will engage contact 15.

Indicated generally at 17 is a safety switch which comprises a pair of resilient contact blades 18 and 19 which are biased to open circuit position but which are normally held closed by means of a bimetallic blade 20. This blade is connected at its lower end to a second bimetallic blade 21, which in turn is connected to the bimetallic blade 22, one end of which is fixed. The blades 20 and 21 are adapted to be heated by means of an electrical heater 23, which upon being energized causes the blades 20 and 21 to warp in a direction to move the upper end of the blade 20 from beneath the flexible contact blade 19 and permit it to move to open circuit position. After this action has once taken place, a subsequent cooling

of blades 20 and 21 will be incapable of returning switch blade 19 to closed circuit position. This must be accomplished manually by the trip free reset member 25. The safety switch 17 has been illustrated more or less diagrammatically and may take any one of many forms. One of the forms which this device may take is illustrated in the patent to Miller No. 2,237,262.

Illustrated at 27 is a conventional type of combustion responsive switch which is closed cold. This switch is shown as comprising a switch arm 28 which cooperates with a stationary contact 29, and for the purposes of illustration is shown as being actuated by means of a bimetal helix 30. It is customary to connect the helix 30 with the switch arm 28 through a slip friction connection so that the switch arm will be actuated upon a reversal in temperature change rather than upon the attainment of any predetermined temperature. It will be appreciated that any other form of combustion responsive switch may be substituted for the device illustrated.

The control system is intended to control the usual type of oil burner motor indicated at 32 and the oil delivered to the combustion chamber of the furnace by this motor is to be ignited by means of an ignition device 33.

Indicated at 40 is a relay winding which is adapted to control switch arms 41 and 42 which cooperate respectively with stationary contacts 43 and 44. When the relay winding is energized the switch arms are moved into engagement with their stationary contacts, and when the winding is deenergized these arms move out of engagement with the stationary contacts through a biasing spring or by means of gravity.

Electrical power is supplied to the control system by means of the line wires 34 and 35, which feed the primary winding 36 of a step-down transformer 37 by means of conductors 38 and 39.

Operation

The parts are shown in the drawing in the position which they will assume when the room thermostat 10 is satisfied and hence the resilient contact blades 12 and 13 are out of engagement with their respective stationary contacts 14 and 15. The relay winding 40 will therefore be deenergized and the contact arms 41 and 42 will be in open circuit position and the burner motor 32 and ignition device 33 will be deenergized. Combustion will not be present in the furnace and therefore the switch arm 28 will be in engagement with its stationary contact 29. The

heater 23 for the safety switch 17 will be deenergized and hence the thermal blades 20 and 21 will be in cold position, at which time they will hold contact blades 18 and 19 closed.

As a result of the above condition, the temperature in the room in which the thermostat 10 is located will begin to decrease. This will first cause the resilient contact blade 12 to engage its stationary contact 14 which will have no immediate effect upon the system due to the fact that the contact arm 41 is in open circuit position. A further decrease in room temperature will cause contact blade 13 to engage its stationary contact 15. This will establish a circuit for the relay winding 40 which may be traced as follows: from one side of the secondary winding 46 of the transformer 37, through conductor 47, stationary contact 14, contact blades 12 and 13, contact 15, conductor 48, relay winding 40, conductor 49, contact 29, switch arm 28, conductors 50 and 51, 15 heater 23, conductor 52, switch blades 18 and 19, and conductor 53 back to the other side of the secondary winding 46. The above circuit will cause energization of both the relay winding 40 and the electric heater 23 for the safety switch. Energization of the safety switch heater 23 will cause the thermal blades 20 and 21 to warp in a direction to trip the safety switch blade 19 to open circuit position. Energization of the relay winding 40 will cause switch arms 41 and 42 to engage their stationary contacts 43 and 44. Switch arm 41 closes a holding circuit for the relay winding 40 which is independent of switch blade 13 and contact 15. This circuit may be traced from one side of the secondary winding 35 46 through conductor 47, contact 14, switch blade 12, bimetal 11, conductor 55, contact 43, switch arm 41, conductor 56, relay winding 40, conductor 49, contact 29, switch arm 28, conductors 50 and 51, heater 23, conductor 52, contact blades 18 and 19, and conductor 53 back to the other side of the secondary winding 46.

Engagement of contact arm 42 with the contact 44 establishes a circuit from line wire 34 through conductor 58, switch arm 42, contact 44, conductors 59 and 60, burner motor 32, and conductor 61 back to the other line wire 35. This connects the burner motor 32 across the two line wires 34 and 35 and hence causes its energization. The ignition device 33 is connected in parallel with the burner motor 32 by the conductors 62 and 63 and hence the ignition device is energized simultaneously with the burner motor 32.

If combustion is not established, the thermal blades 20 and 21 will continue to heat and will after a predetermined period of time permit switch blade 19 to move to open circuit position. As set forth above, this blade cannot be returned to closed circuit position without the manual operation of the reset member 25.

Normally, however, when the burner motor 32 and ignition device 33 are energized, combustion will take place. In response to the establishment of combustion, the combustion responsive switch arm 28 will separate from its stationary contact 29, thus breaking the original energizing circuit for the relay winding 40 and the electric heater 23. It will be noted, however, that there is a shunt circuit around the combustion responsive switch 28, 29. This circuit comprises conductor 65, electric heater 66, and conductor 67. The circuit for the relay winding 40 and the electric heater 23 now includes the electric heater 66 and therefore the current flow is reduced. This re-

duction is current, however, is not sufficient to drop out the relay 40 and therefore the burner motor 32 and ignition device 33 remain energized. In addition to reducing the current flow through the heater 23 which is heating the thermal blades 20 and 21, the heater 66 heats thermal blade 22 which is so arranged that on an increase in temperature it warps in a direction to maintain the free end of thermal blade 20 in latching engagement with the switch blade 19. In fact, this thermal blade 22 is the usual compensating blade for the thermal safety switch which normally compensates it for variations in ambient temperature. Therefore, if the blade 22 is heated to the same temperature as the blades 20 and 21, the free end of the blade 20 will occupy the same position as it occupies when all of the thermal elements are cold. Therefore energization of the heater 66 prevents the heater 23 from causing the thermal blades 20 and 21 from opening the safety switch 18, 19.

On an increase in room temperature, the switch blade 13 will separate from contact 15. This will have no effect upon the system due to the holding circuit for the relay winding 40 which passes through switch arm 41 and contact 43. With a further increase in room temperature the switch blade 12 will separate from contact 14 and de-energize the relay winding 40 as well as both of the electric heaters 23 and 66. This will result in a complete deenergization of the system.

The resistance values of the two heaters 23 and 66 are so chosen that should the two resilient blades 12 and 13 be moved into engagement with their contacts 14 and 15 while the combustion switch 27 is in open circuit position, the current flow through the relay winding 40 will be insufficient to pull it in. Therefore, after the system has once been shut down, it cannot be reenergized until the combustion switch 27 is moved to closed circuit position, thereby shunting the heater 66. In other words, the combustion switch 27 times the scavenging period upon a shut-down from the room thermostat or on a shut-down due to a power failure.

If a flame failure should occur when the system is in running condition, the switch arm 28 will be moved into engagement with its contact 29 thereby shunting the electric heater 66. This will effectively deenergize this heater and will increase the energization of the heater 23 and after a predetermined period of time the thermal blade 20 will move from beneath contact blade 19, whereupon this blade will move to open circuit position and the system will be effectively locked out.

It will therefore be seen that I have designed a system which is relatively simple and inexpensive in that it utilizes a single relay, a two wire combustion switch, and a safety switch and yet one which will protect against a momentary power failure by interposing a scavenging period before the burner motor can be reenergized and one which will check itself each cycle for a burned out safety switch heater. This last result is obtained because if the heater 23 burns out at any time the circuit to the relay winding 40 will be broken and hence the burner motor and ignition device cannot be energized. Therefore there is always protection in so far as the operation of the safety switch is concerned.

Various changes and modifications of this invention may occur to those who are skilled in the art, and I therefore wish it to be understood that 75 I intend to be limited by the scope of the ap-

pended claims and not by the specific embodiment disclosed.

I claim as my invention:

1. A fuel burner control system comprising in combination, an electrical fuel feeding device, an electrical relay in control thereof, a thermal timer comprising an actuating thermostat and a compensating thermostat, a first heater for said actuating thermostat, a second heater for said compensating thermostat, a closed cold stack switch continuously connected in shunt with said second heater, a main switch, and an energizing circuit for pulling in said relay comprising said main switch, stack switch and first heater, energization of said first heater causing said actuating thermostat to deenergize said electrical fuel feeding device after a predetermined period of time, the establishment of combustion causing said combustion switch to open thereby energizing said second heater to prevent said actuating thermostat from deenergizing said fuel feeding device, said second heater having an impedance such that said relay can be held in but not pulled in when said combustion switch is open.

2. A fuel burner control system comprising in combination, an electrical device in control of fuel feed, a thermal timer for controlling the energization of said device comprising an actuating temperature responsive device and a compensating temperature responsive device, a first electrical heater for said actuating temperature responsive device, a second electrical heater for said compensating temperature responsive device, a main control switch, combustion responsive means including a closed cold combustion switch, an energizing circuit for said device including said main control switch, said cold closed com-

bustion switch, and said first heater, said thermal timer being effective upon the continued energization of said first heater alone to cause deenergization of said electric device, and circuit connections continuously connecting said second heater across the terminals of said closed cold combustion switch so that upon said combustion switch opening in response to the establishment of combustion, said first and second heaters are effectively connected in series in said energizing circuit.

3. A fuel burner control system comprising in combination, an electrical device in control of fuel feed, a safety switch for controlling the energization of said device comprising an actuating temperature responsive device and a compensating temperature responsive device, a first electrical heater for said actuating temperature responsive device, a second electrical heater for said compensating temperature responsive device, a main control switch, combustion responsive means including a closed cold combustion switch, an energizing circuit for said device including said main control switch, said cold closed combustion switch, said safety switch, and said first heater, said safety switch being effective upon the continued energization of said first heater alone to open and cause deenergization of said electric device, and circuit connections continuously connecting said second heater across the terminals of said closed cold combustion switch so that upon said combustion switch opening in response to the establishment of combustion, said first and second heaters are effectively connected in series in said energizing circuit.

ROBERT S. CRAIG.
